HUNT, HELM, FERRIS & COMPANY, OF HARVARD, ILLINOIS, A CORPORATION OF
ILLINOIS.

MANGER.

1,121,176.

Specification of Letters Patent. Patented Dec. 15, 1914.

Application filed September 2, 1913. Serial No. 787,668.

To all whom it may concern:

Be it known that we, HENRY L. FERRIS and HOWARD J. FERRIS, citizens of the United States, residing at Harvard, in the county of 5 McHenry and State of Illinois, have invented a new and useful Improvement in Mangers, of which the following is a specification.

Our invention relates to certain new and 10 useful improvements in mangers and is fully described and explained in the specification and shown in the accompanying drawings, in which:—

Figure 1 is a section on the line 1 of Fig. 15 2, that is a view showing everything except the forward wall of the manger in side elevation; Fig. 2 is a section on the line 2 of Fig. 1, this view thus showing the major parts of the structure in top plan; Fig. 3 20 is a section on the line 3 of Fig. 2 and on a somewhat larger scale; and Fig. 4 is a section on the line 4 of Fig. 3.

Referring to the drawings, 6 is the curb of the stall to which the manger is applied, 25 the stall proper being to the rear thereof and the floor in front of the curb being provided with a trough 7 forming the bottom of the manger.

8 are manger-partitions, to the forward 30 edges of which is attached a manger-front 9.

As a measure of convenience the mangers are made in separate units, preferably one unit for each three stalls, as herein shown, so that each manger-front is attached to 35 four of the partitions 8, one at each end and two intermediate. To stiffen each unit thus formed, an angle-iron 10 is extended along the upper forward corner of the unit, the angle of said angle-iron extending forwardly, whereby one flange is in the plane of 40 the manger-front 9 and the other flange extends diagonally upward and backward, as shown.

Mounted upon the curb 6, opposite the 45 vision lines between the stalls are castings 11, each of which has adjustably attached to it the lower corners of the two adjacent stall-fronts 12, the said stall-fronts carrying, in the usual manner, stanchions which are 50 shown in section in Fig. 2 and designated 13. Each stall is thus provided with an adjustable stanchion-carrying frame of the

type broadly claimed in our Patent No. 1,066,194, and having the advantages therein set forth.

Heretofore it has been the practice when using a pivoted manger to carry the same upon the framework of the stall, but when the adjustable stanchion-carrying stall-front is used to secure the manifest advantages 60 of that construction, it is a matter of considerable difficulty to supply a manger-support adaptable for stalls of all types, since some stalls have practically no stationary framework, and in any event the stationary 65 parts upon which the adjustable front is mounted vary so much in type as to necessitate special manger-supports for the special types, if any effort is to be made to support the manger from the framework. However, 70 whatever be the type of stall construction adopted, there is provided in all cases, for the adjustable stanchion-carrying front as used in accordance with our designs a casting set in the curb substantially similar to 75 that herein shown, and designated by the numeral 11. This we utilize as the manger-carrying means, thereby securing a device which is thoroughly efficient whatever be the type of stall construction.

Each of the castings 11 is slotted at 14 and to its upper surface is bolted a plate 15 having an upwardly projecting flat ear 16 lying in a plane longitudinal of the stall. Embracing the rear edges of the manger-partitions 8 are hinge-members 17 each of which has at its rear end two ears 18 embracing the ears 16 and pivoted thereto, so that the manger can be swung up from the position shown in solid to that shown in dotted lines 90 in Fig. 1. The upward swinging of the manger is limited by engagement of the angle-iron 10 with whichever of the stall-fronts in the series happens to be adjusted in the forwardmost position.

For the purpose of assisting in raising the manger and holding it in its raised position, the spring mechanism shown is provided at one or more of the pivots. We prefer to employ spring mechanism only at the intermediate pivots of the manger, leaving the end pivots as shown without the spring means. In the structure illustrated here, the spring means is shown only at intermediate

pivots and it is to be understood that all the parts heretofore described are substantially identical both at the end pivots where there is no spring means, and at the intermediate pivots where the spring means is provided.

One of the intermediate pivots will now be particularly described to elucidate the construction of the spring means. The castings 10 11 are provided with rearwardly extending ears 19, which afford pivotal support to a shaft 20 having a squared intermediate portion adapted to engage the inner end of a spring 21.

15 The opposite end of the spring is hooked to engage a pin 22 adjustable into any of a series of holes 23 in the ears 19, whereby the spring tension can be varied. The shaft 20 has projecting from it radial arms 24 connected by means of a link 25 hooked over said arms, with the hinge-member 17, the pivot of the link thereon being so placed that when the manger is down the link lies quite close to the pivot of the manger. In 20 other words, when the manger is down the spring tension is along a line close to the dead center, and the spring therefore exerts but slight elevating force. As the manger rises, however, the efficiency of the spring 25 increases, so that when in its upper position the manger is held firmly against displacement.

The present device is advantageous, not only for the reasons already pointed out, 30 but further because of the simplicity and efficiency of the spring means. The spring means is readily adjustable to different degrees of tension. Furthermore when the manger is erected by unskilled help, as it 35 often is, the spring need not be under tension. In devices for a similar purpose heretofore employed, the spring has been under continuous tension, or, if not, it was a matter of greatest difficulty to place it under 40 tension without special tools. With the present device the several parts are set together without any tension on the spring, the wrench is placed on the squared outer end of the shaft 20, which is rotated in a 45 direction to throw the arms 24 far enough forward, against the tension of the spring for the link 25 to be hooked over them. This will preferably occur when the manger 50 is in elevated position. Any irregularities in 55 the tension of the springs can be taken up by the adjustment shown.

It is manifest that the present device is capable of considerable variation without departing from the spirit of our invention, 60 as we do not intend to limit ourselves to the specific form herein shown, except as pointed out in the following claims, in which it is our intention to claim all the novelty in-

herent in the device as broadly as is permitted by the state of the art.

We claim as new and desire to secure by Letters Patent—

1. In combination, a curb and a trough in front of the same, a manger pivotally mounted on the curb, and means mounted 70 on the curb for exerting elevating force on the manger.

2. In combination, a curb, a trough in front of the same, a casting carried by the curb, a manger receiving pivotal support 75 from the casting, and means carried by the casting for exerting elevating pressure on the manger.

3. In combination, a curb, a trough in front of the same, a casting, a member longitudinally adjustable on the casting, a manger pivoted to said member, and spring means connecting the manger and casting to elevate the manger.

4. In combination, a curb, a trough in 85 front of the same, a casting mounted on the curb and having rearwardly extending ears, a coiled spring carried between said ears, means for locking one end of the spring in stationary position, and a link having means 90 of connection with the opposite end of said spring at one end, and at the other engaging the manger.

5. In combination, a curb, a trough in 95 front of the same, a casting mounted on the curb and having rearwardly extending ears, a coiled spring carried between said ears, means for locking one end of the spring adjustably in stationary position, and a link having means 100 of connection with the opposite end of said spring at one end, and at the other engaging the manger.

6. In combination, a curb, a trough in front of the same, a casting mounted on the curb and having rearwardly extending ears, 105 a shaft mounted in said ears and carrying a coiled spring, radial arms on the shaft, a manger receiving pivotal support from the casting, and a link connecting the outer end of said arms with the manger.

7. In combination, a curb, a trough in front of the same, a casting mounted on the curb and having rearwardly extending ears, a shaft mounted in said ears and carrying a 115 coiled spring, radial arms on the shaft, a manger receiving pivotal support from the casting, and a link connecting the outer end of said arms with the manger, and means for adjusting the outer end of the spring to secure variations in the tension thereof.

HENRY L. FERRIS.
HOWARD J. FERRIS.
